CLAIM

The ornamental design for a charging stand for smartphone, tablet or smartwatch, as shown and described.

DESCRIPTION

FIG. 1 is a front elevation view of a charging stand for smartphone, tablet or smartwatch showing my new design; FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof; and,

FIG. 7 is a right bottom rear perspective view thereof.

The broken lines in the drawings depict boundaries of the charging stand for smartphone, tablet or smartwatch that form no part of the claimed design.
